(57) **CLAIM**

The ornamental design for a mobile radiotelephone apparatus, as shown and described.

DESCRIPTION

FIG. 1 is a perspective view of the mobile radiotelephone apparatus in accordance with the present invention with the cover being in an extended state to enable using the device; FIG. 2 is a front plan view of the mobile radiotelephone apparatus of FIG. 1;

FIG. 3 is a back plan view of the mobile radiotelephone apparatus of FIG. 1;

FIG. 4 is a left side view of the mobile radiotelephone apparatus of FIG. 1;

FIG. 5 is a right side view of the mobile radiotelephone apparatus of FIG. 1;

FIG. 6 is a top end view of the mobile radiotelephone apparatus of FIG. 1;

FIG. 7 is a bottom end view of the mobile radiotelephone apparatus of FIG. 1;

FIG. 8 is a perspective view of the mobile radiotelephone apparatus of FIG. 1 in a closed condition;

FIG. 9 is a front plan view of the mobile radiotelephone apparatus in the closed condition illustrated in FIG. 8;

FIG. 10 is a back plan view of the mobile radiotelephone apparatus in the closed condition illustrated in FIG. 8;

FIG. 11 is a left side view of the mobile radiotelephone apparatus of FIG. 9 in the closed condition; and,

FIG. 12 is a right side view of the mobile radiotelephone apparatus of FIG. 9 in the closed condition.
